UNITED STATES PATENT OFFICE.

GEORGE JOHNSTON, OF DETROIT, MICHIGAN.

DESIGN FOR AN EYEGLASS-GUARD.

No. 38,271.

Specification for Design.

Patented Oct. 9, 1906.

Application filed November 9, 1905. Serial No. 286,614. Term of patent 14 years.

To all whom it may concern:

Be it known that I, GEORGE JOHNSTON, a citizen of the United States, residing at Detroit, county of Wayne, State of Michigan, have invented a certain new, ornamental, and original Design for Eyeglass-Guards, of which the following is a specification, reference being had to the accompanying drawing, which forms a part of this specification.

The figure is an enlarged view in elevation

of an eyeglass-guard, showing my new design.

I claim—

The ornamental design for an eyeglass-guard, as shown.

GEORGE JOHNSTON.
